CLAIM

The ornamental design for a solar pathway light, as shown and described.

DESCRIPTION

FIG. 1 is a top perspective view of a solar pathway light, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of FIG. 1, shown in an alternate state of use; and,

FIG. 10 is a perspective view of FIG. 1, shown in an alternate state of use.

The additional lights shown in FIGS. 9 and 10 illustrate environmental structure of the solar pathway light; all other broken lines represent portions. The broken lines form no part of the claimed design.

1 Claim, 10 Drawing Sheets
